UNITED STATES PATENT OFFICE.

BENJAMIN BALSER, OF DES MOINES, IOWA.

SHOE-SHINING FOOT-REST.

1,168,271.

Specification of Letters Patent. Patented Jan. 18, 1916.

Application filed June 4, 1914. Serial No. 842,935.

To all whom it may concern:

Be it known that I, BENJAMIN BALSER, a citizen of the United States, and a resident of the city of Des Moines, in the county of 5 Polk and State of Iowa, have invented a certain new and useful Shoe-Shining Foot-Rest, of which the following is a specification.

The object of my invention is to provide 10 a mechanism or contrivance that will obviate and avoid all the inconvenience and danger surrounding the old-fashioned vertical and fixed foot rests used in connection with shoe shining chairs. The invention is to operate 15 in such way as to leave the space immediately in front of the chair unobstructed, thereby permitting a free and easy mounting to and descending from the chair without inconvenience and without danger of 20 damage or injuries to the clothing, person or body of the person whose shoes or boots are shined.

A further object of my invention is to provide a mechanism or contrivance that 25 will render itself adjustable to the varying physical proportions of the parties whose shoes or boots are shined and thereby avoid the inconvenience to operator and patron resulting from the fixed, rigid and immovable 30 foot rests.

I attain the objects above stated by the mechanism and contrivance illustrated in the accompanying drawing, in which—

Figure 1 is a view of the invention looking down upon it from above; Fig. 2 is a side view showing its position with relation to the chair in which the patron, customer or party, having his shoes shined, sits; Fig. 3 is a cross section of the invention at the 35 point where the pin (hereinafter fully explained) is situated, the cross section having been taken at the place indicated in Fig. 1 by the arrows.

Similar letters refer to similar parts 40 throughout the several views.

A is a hexagonal hollow cylinder, lying down on one of its long faces, with the lower base B closed and the upper base C open. Through C is inserted a hexagonal solid 45 cylinder D, slightly smaller in diameter than A and fitting snugly inside of A throughout the whole length thereof. The hollow cylinder A permits the solid cylinder D to be pushed back and forth inside of A. When D is pushed its entire length throughout and inside of A, the free end of the

former, E will coincide with C. In other words D may be regarded as the hollowed out portion of A and when D is fully inside of A, the latter may be considered as a 60 hexagonal solid cylinder.

The free end of D as shown in Fig. 2 bears a two branched support F upon which rests an ordinary sole piece G, commonly seen in all shoe shining parlors or establishments, said G being made to conform and fit the ordinary sole of a shoe. An upright H, extends from the upper extremity of D perpendicularly as far as the under surface of the sole piece G and up against 65 the farthermost branch of the support F, as shown in Fig. 2. This upright H acts and serves as a handle which the bootblack grasps or takes hold of in order to push and drive D in and out of A.

A bears a slit on its uppermost surface shown in Fig. 1 as I, which slit in length is equal to the distance from J (Fig. 2) to the end of the cylinder D and a trifle wider than the thickness of the support F, so as to permit the support F to slide back and forth inside of I. The uppermost surface of A bears another slit K which commences a small distance from B, the closed end of A, as shown in Fig. 1, and extends a varying 70 distance along the length of A, preferably a distance slightly more than half the length of A. D at its unfree end bears several grooves or sockets L, as shown in Fig. 1, bored into it through a distance of about one 75 third its thickness and of a diameter equal to the width of the slit K. These grooves and sockets are made to receive and hold a movable pin as shown in Figs. 2 and 3, which pin is of the thickness slightly less than the grooves and sockets L, and the width of the slit K, so that it can be inserted through the slit K and into any of the 80 grooves or sockets L and will project vertically a distance above the uppermost surface of A equal to about one-third the perpendicular height of H.

The hollow cylinder A lying flat on its undermost surface O, sets into a semi-hexagonal support or casing N, N¹, N², so 85 formed as to receive snugly and tightly this surface O and its two adjacent faces O¹ and O². The hexagonal supports or casings, as shown in Figs. 1 and 2, are placed one at a slight distance from each of the ends 90 of A and one in the center thereof. These semi-hexagonal supports N, N¹, N², 95

rest on rectangular bases P, P¹, P², which protrude on each side beyond the hexagonal supports or casings, as shown in Figs. 1 and 3. The bases bear near each end thereof a hole, which will permit the passing of a screw or bolt through same in order to fasten the entire mechanism in place.

In Fig. 1, D is shown as partly extended out of A; in Fig. 2, the dotted portion represents D also extended but giving a better idea of the working of the mechanism. The pin M, being movable and insertible in any of the sockets L, enables the bootblack or operator to extend D out of A a varying distance to suit his own pleasure and that of the party whose shoes or boots are being shined.

The entire mechanism may be placed on the base or platform on which the chair rests, outside of the side legs thereof or between the side legs thereof. In Fig. 2, the mechanism is shown as placed outside of the side legs of the chair, with the part bearing the foot rest in front.

The mechanism is to be placed so that when it is not in its extended position, it will not protrude beyond the base or platform to which it is fastened. By correct use of the mechanism as hereinafter stated the advantages of my invention will be attained. When no one is occupying the chair, D is fully inside of A leaving the entire space in front of the chair vacant and unencumbered, thus giving a natural, easy and free access to the chair. When the party sits in the chair to have his shoes shined, the bootblack or operator will then extend D out of A a suitable distance so that the foot piece G will be in front of the chair and ready to receive the foot of the party whose shoes are to be shined. When the shoe shining operation is completed, the bootblack or operator will push D inside of A, again leaving the space in front of the chair vacant

and unencumbered and thus affording the party whose shoes are shined, a natural, free and easy manner of stepping down from the chair onto the floor.

The cylinders, D and A, may be circular or polygonal. The advantage gained in using the polygonal shape, such as a hexagon, is that the twisting and turning of D inside of A is prevented, though in the circular shape, the pin M should be sufficient to prevent such twisting and turning.

I claim—

1. A tubular horizontally mounted base member having a slot at its top which opens through the front end of said member and also having a second slot at its rear the front wall of which second slot forms a stop, a bar slidable in said member, a foot rest secured to the bar and extending up through the front slot, said bar having a series of spaced apertures which register with the rear slot, and a pin for selective engagement in any one of the apertures and with the stop.

2. A tubular horizontally mounted base member having a slot at its top which opens through the front end of said member and also having a second slot at its rear the front wall of which second slot forms a stop, a bar slidable in said member, a foot rest secured to the bar and extending up through the front slot, said bar having a series of spaced apertures which register with the rear slot, a pin for selective engagement in any one of the apertures and with the stop, and a vertical member connected to the bar and extending through the front slot and engaged with the foot rest to provide a hand grip.

BENJAMIN BALSER.
